J. N. MODISETT

DEEP WELL PUMPING APPARATUS

Filed May 27, 1924

Patented May 12, 1925.

1,537,487

UNITED STATES PATENT OFFICE.

JOHN N. MODISETT, OF HERMOSA BEACH, CALIFORNIA.

DEEP-WELL PUMPING APPARATUS.

Application filed May 27, 1924. Serial No. 716,240.

To all whom it may concern:

Be it known that I, JOHN N. MODISETT, a citizen of the United States, residing at Hermosa Beach, in the county of Los Angeles and State of California, have invented certain new and useful Improvements in Deep-Well Pumping Apparatus, of which the following is a specification, reference being had to the accompanying 10 drawings.

This invention relates to deep well pumping apparatus and more particularly to an improvement in that type of pumping apparatus usually employed in oil wells.

15 An important object of the invention is to provide for pumping apparatus of this character an attachment for the standing valve and working barrel of the pumping apparatus whereby upon a predetermined 20 operation of the tubing constituting the pumping line the standing valve is unseated.

It is well known to those familiar with the art that these standing valves are often 25 very difficult to unseat, being subjected to a pressure head equal to the height of the line above the working barrel and, in addition, being subject to sanding caused by precipitation of fine sediment, as sand and the like, carried into the working barrel 30 by the oil and there deposited. This sanding often becomes so severe as to actually prevent operation of the standing and working valves of the barrel and accordingly a still further object of the invention is the 35 provision of means whereby the sand may be drained from the working barrel without complete removal of the standing valve from the well.

40 A further object of the invention is to provide a device of this character which accomplishes shifting of the standing valve without the necessity of attempting the hoisting thereof with the sucker rods which in such attempts are often parted thereby necessitating pulling of the entire tubing, 45 working barrel and associated parts to repair the breakage.

These and other objects I attain by the construction shown in the accompanying 50 drawings, wherein for the purpose of illustration is shown a preferred embodiment of my invention and wherein:—

55 Figure 1 is a side elevation of apparatus constructed in accordance with my invention in position within a well and in the

position in which it remains during pumping operations;

Figure 2 is a sectional view showing the device in the position it assumes when the casing is lowered;

Figure 3 is an enlarged sectional view through the device;

Figure 4 is a transverse sectional view on the line 4—4 of Figure 3.

Referring now more particularly to the drawings, the numeral 10 indicates an oil well casing within which is disposed the usual tubing 11 having at its lower end a working barrel 12 in the lower end of which is seated a standing valve 13.

In accordance with my invention I couple to the lower end of the working barrel 12 a short length of pipe 14 which is preferably perforated. This pipe may, if so desired, be in the form of a well screen of 75 the proper diameter and preferably of the same diameter as the working barrel. To the lower end of the standing valve 13 I secure a conduit 15 which projects downwardly from the lower end of the valve 80 through the lower end of the working barrel and into the pipe or screen 14, this conduit being of less length than the conduit 14 and of considerably less diameter.

At the lower end of the conduit or screen 85 14 I secure a head 16 through which is slidably axially directed a second section of conduit 17 which is slidably engaged with the head 16 and has within the screen 14 a head 18 of less diameter than the interior of 90 the screen 14 and between this head and the head 16 a cushioning spring 19 is inserted. The conduit 17 is preferably provided with a coupling or shoulder 20 forming a seat for the lower end of a second spring 21 and a 95 limit for downward movement of the head 16 upon the conduit 17. The bore of the conduit 17 is of a size to receive the pipe extension 15 of the standing valve and has therein adjacent the upper end thereof a 100 spider 22 the purpose of which will presently appear.

In the use of the device the device is installed before the lowering of the pump tubing and working barrel into the well. In 105 event of sanding up of the well the working barrel, together with the tubing, is lowered permitting the lower end of the conduit 17 to come to rest upon the lower end of the well, lowering being continued until the 110

lower end of the head 16 comes into engagement with the stop shoulder 20 or more particularly with the spring 21 supported from this stop shoulder. Prior to this engagement the lower end of the conduit 15 has come to rest upon the spider 22 and the standing valve 13 has been forced upwardly for this reason.

In the construction of the attachment care is taken that the length of the several parts employed is such that when the lower end of the head 16 is in engagement with the stop 20 or shortly prior to the time when it comes into such engagement the valve 13 is projected above the upper end of the working barrel, with the result that oil and sand within the tubing may pass downwardly through the working barrel and through the conduits 15 and 17. To accomplish this the pipe 15 must be of greater length than the length of the working barrel.

It will be obvious that the construction herein illustrated is but one of many types of construction which might be employed to accomplish the same result and I accordingly do not limit myself to such specific structure as hereinbefore set forth except as hereinafter claimed.

I claim:

1. In oil well pumping apparatus and in combination with the usual working barrel and standing valve therein, a telescopic element engaged at its upper end with the lower end of the working barrel and adapted at its lower end for engagement with the bottom of a well, means limiting the telescopic engagement of the sections of the element, and means carried by the lower end of the standing valve and projecting into said telescopic element engaging a portion of said telescopic element during telescoping thereof to thereby lift the standing valve above the upper end of the working barrel.

2. In deep well pumping apparatus and in combination with the usual well contained unit including tubing, working barrel carried thereby, and standing valve seated within the working barrel, means supported from the bottom of the well and guided from the lower end of the working barrel operatively engaging the standing valve during downward movement of the well contained unit from its normal or pumping position to unseat the standing valve and elevate the same above the upper end of the working barrel.

3. In deep well pumping apparatus and in combination with the usual well contained unit including tubing, working barrel carried thereby, and standing valve seated within the working barrel, means supported from the bottom of the well and guided from the lower end of the working barrel operatively engaging the standing valve during downward movement of the

well contained unit from its normal or pumping position to unseat the standing valve and elevate the same above the upper end of the working barrel, including a guide carried by the lower end of the working barrel, a member telescopically engaged with the guide and shiftable therethrough toward the lower end of the working barrel, means on said member limiting downward movement of the guide thereon prior to engagement of the lower end of the working barrel with the member, and a stem secured to the lower end of the working barrel and with which said member engages, the stem of said standing valve being of a length sufficient to elevate the standing valve above the upper end of the working barrel when the guide is in its lowermost position.

4. In deep well pumping apparatus and in combination with the usual well contained unit including tubing, working barrel carried thereby, and standing valve seated within the working barrel, means supported from the bottom of the well and guided from the lower end of the working barrel operatively engaging the standing valve during downward movement of the well contained unit from its normal or pumping position to unseat the standing valve and elevate the same above the upper end of the working barrel, including a guide carried by the lower end of the working barrel, a member telescopically engaged with the guide and shiftable therethrough toward the lower end of the working barrel, means on said member limiting downward movement of the guide thereon prior to engagement of the lower end of the working barrel with the member, a stem secured to the lower end of the working barrel and with which said member engages, the stem of said standing valve being of a length sufficient to elevate the standing valve above the upper end of the working barrel when the guide is in its lowermost position, said member having a head limiting its downward movement through the guide, and a spring disposed between said head and guide.

5. In deep well pumping apparatus and in combination with the usual well contained unit including tubing, working barrel carried thereby, and standing valve seated within the working barrel, means supported from the bottom of the well and guided from the lower end of the working barrel operatively engaging the standing valve during downward movement of the well contained unit from its normal or pumping position to unseat the standing valve and elevate the same above the upper end of the working barrel, including a guide carried by the lower end of the working barrel, a member telescopically engaged with the guide and shiftable therethrough toward the lower end of the working barrel, means on

- said member limiting downward movement of the guide thereon prior to engagement of the lower end of the working barrel with the member, a stem secured to the lower end 5 of the working barrel and with which said member engages, the stem of said standing valve being of a length sufficient to elevate the standing valve above the upper end of the working barrel when the guide is in its 10 lowermost position, said means for limiting downward movement of the guide comprising an upwardly facing shoulder on the member, and a spring seated upon said shoulder.
- 15 6. In deep well pumping apparatus and in combination with the usual well contained unit including tubing, working barrel carried thereby, and standing valve seated within the working barrel, means supported 20 from the bottom of the well and guided from the lower end of the working barrel operatively engaging the standing valve during downward movement of the well contained unit from its normal or pumping position 25 to unseat the standing valve and elevate the same above the upper end of the working barrel, including a guide carried by the lower end of the working barrel, a member telescopically engaged with the guide and 30 shiftable therethrough toward the lower end of the working barrel, means on said member limiting downward movement of the guide thereon prior to engagement of the lower end of the working barrel with the 35 member, and a stem secured to the lower end of the working barrel and with which said member engages, the stem of said standing valve being of a length sufficient to elevate the standing valve above the upper end of the working barrel when the guide is in its 40 lowermost position, said guide being in the form of a tubular screen having a head at its lower end through which the member is directed.
7. In deep well pumping apparatus and in combination with the usual well contained unit including tubing, working barrel carried thereby, and standing valve seated within the working barrel, means supported 45 from the bottom of the well and guided from the lower end of the working barrel operatively engaging the standing valve during downward movement of the well contained unit from its normal or pumping position to 50 unseat the standing valve and elevate the same above the upper end of the working barrel, including a guide carried by the lower end of the working barrel, a member telescopically engaged with the guide and shiftable therethrough toward the lower end 55 of the working barrel, means on said member limiting downward movement of the guide thereon prior to engagement of the lower end of the working barrel with the member, a stem secured to the lower end of the working barrel and with which said member engages, the stem of said standing valve being of a length sufficient to elevate the standing valve above the upper end of the working barrel when the guide is in its 60 lowermost position, said guide being in the form of a tubular screen having a head at its lower end through which the member is directed, the member having a head operated within the screen, and a spring between the heads of the guide and member.
- In testimony whereof I hereunto affix my signature.

JOHN N. MODISETT.
